(57) **CLAIM**

The ornamental design for a backpack with an LCD screen and speakers in combination, as shown and described.

DESCRIPTION

FIG. 1 is a rear perspective view of a backpack with an LCD screen and speakers in combination, showing a first embodiment of my new design;

FIG. 2 is a rear elevational view of FIG. 1;

FIG. 3 is a front elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is a rear perspective view of a second embodiment thereof;

FIG. 9 is a rear elevational view of FIG. 8;

FIG. 10 is a front elevational view of FIG. 8;

FIG. 11 is a left-side elevational view of FIG. 8;

FIG. 12 is a right-side elevational view of FIG. 8;

FIG. 13 is a top plan view of FIG. 8; and,

FIG. 14 is a bottom plan view of FIG. 8.

The broken lines across the speakers of the design and the broken lines on the interior of the pockets illustrate portions of the backpack with an LCD screen and speakers in combination that form no part of the claimed design. The remaining broken lines in the figures illustrate stitching, and are part of the claimed design.
